UNITED STATES PATENT OFFICE.

EVERETT J. HALL, OF PASSAIC, NEW JERSEY, ASSIGNOR TO METALS DISINTEGRATING COMPANY, INC., OF NEW YORK, N. Y., A CORPORATION OF NEW YORK.

NOZZLE INTENDED FOR USE IN DISINTEGRATING APPARATUS.

Application filed March 25, 1919, Serial No. 285,002. Renewed October 30, 1922. Serial No. 598,013.

To all whom it may concern:

Be it known that I, EVERETT J. HALL, a citizen of the United States, residing at Passaic, in the county of Passaic and State of New Jersey, have invented certain new and useful Improvements in Nozzles Intended for Use in Disintegrating Apparatus, of which the following is a specification.

This invention relates to the construction of nozzles intended for use in disintegrating apparatus of the sort shown in my co-pending applications Serial Nos. 208,166, 208,165 and 117,161. In such apparatus moulten metal or material issues from a nozzle and is disintegrated by the force of a jet of steam or other fluid which surrounds the nozzle. In some cases the force of the disintegrating blast is utilized also to create a suction whereby the moulten metal or material is caused to issue from the nozzle. In all cases however, in accordance with my present invention, it is desirable that the disintegrating blast should strike the issuing stream of moulten metal upon converging lines, and it is also desirable that the issuing stream of moulten metal or material, before it is attacked by the disintegrating blast, should be spread out into a film, which passes transversely off of the face of the nozzle into the path of the disintegrating blast.

In addition to attaining the desired fineness and uniformity and maximum production, the present invention contemplates a construction of nozzle in which there is provided a refractory lining for the nozzle which will withstand the solvent action of the liquid metals or materials passing through it and in which the leakage of steam or disintegrating fluid backwardly between the outer nozzle casing and the inner refractory lining, is prevented.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawing the figure illustrates a form of apparatus including a nozzle made in accordance with my inven-

tion which I have found satisfactory in actual practice.

Referring to the numerals on the drawing, there is shown at 1 a tubular member preferably of metal which provides a conduit for the moulten metal or material which is to be disintegrated. This conduit 1 may be in one piece and all metal throughout, but for reasons hereinafter explained, it is desirable in many cases that it should have an interior lining of suitable refractory material, indicated by the numeral 2. In any case the nozzle will have a discharge opening indicated by the numeral 3 which will be of sufficient diameter to allow the moulten metal or material to flow through readily without clogging, but not so much that more metal will flow through than can be properly disintegrated. The end of the nozzle surrounding the discharge opening 3 is preferably concaved as indicated at 4, and along this concaved face the issuing stream of moulten metal or material spreads, until it reaches the sharp edge 5 at the side of the nozzle where it is attacked by the disintegrating blast. The disintegrating blast issues from a steam ring 6 surrounding the forward end portion of the nozzle and defined between the outer wall of the nozzle and the inner wall of an apertured plate 7, which is held in position relatively to the nozzle substantially as shown in the drawing, that is to say with the top of the plate below the discharge end of the nozzle. The outside wall of the nozzle tip, indicated by the reference character 8, is preferably angled as shown, and the surrounding inner wall of the plate 7 is also angled, so that the steam or disintegrating blast will issue from the space 6 on all sides of the nozzle and converging towards the axial line of the nozzle.

The tip of the nozzle being outside of and beyond the steam orifice, the disintegrated metal or material is blown off into space; there is nothing for the material to strike against and build up, nor is there any obstruction for it to hide behind and thereby escape the full action of the steam. A concave construction of the end face 4 of the nozzle has been found to be very satisfactory, preferably with an angle of about fifteen degrees to a plane passing transversely through the plug. The same sort of action can be obtained even with a convex face 4,

so long as the angle is not so acute, with reference to the side wall, as to permit the disintegrating blast to travel along the face 4 towards the central aperture 3, which of course would result in a more restricted flow of material from the aperture 3. I have found that with the concave arrangement of the face 4 at an angle of fifteen degrees as stated, and with the face 8 disposed at an angle of about thirty-five degrees to the axis of the nozzle, very good results are secured. The device shown in the drawing is an embodiment in which the lower end of the nozzle is extended directly into the moulten metal or material, in order to decrease the amount of travel of the metal or material, and particularly in order to keep the nozzle properly heated without the need for applying additional heat over and above that which is stored in the moulten metal supply. Therefore the steam or disintegrating blast issuing from the space 6 should generate only a moderate suction, otherwise there will be a larger supply of metal or material drawn out from the aperture 3 than can be properly finely disintegrated. The strength of this suction may be varied (other factors remaining uniform), by varying the angle of the outside wall 8 of the nozzle. By way of illustration, I have found that for disintegration of moulten zinc a two or three inch lift of the metal from the reservoir to the discharge outlet of the nozzle, with a one-eighth inch discharge opening 3 and a thirty-five degree angle of the face 8, and a fifteen degree angle of the face 4, gives satisfactory results, in that the opening 3 is large enough so that it does not readily clog up and the supply of metal forced through it is such as can be uniformly and finely disintegrated by the disintegrating blast.

It seems impossible to obtain a metal that will withstand the solvent action of all other moulten metals or materials, and therefore it is desirable in some cases to provide the nozzle with a refractory lining like that indicated by the numeral 2. Soapstone may be used for this purpose because it can be turned true and does not warp unduly if carefully burned. When such a refractory lining is used the forward end thereof will be provided with the discharge opening 3 and with the end spreader face 4, and the forward end of this refractory lining will extend beyond the forward end of the metal part of casing 1 of the nozzle and will have its outside forward end, indicated at 9, beveled on an angle to correspond with the angle of the outside angular face 8 of the metal casing. And in order that there may be no leakage of steam into the joint between the forward end of the metal casing and the protruding end of the refractory lining, this joint will be located outwardly beyond the steam ring, that is to say, the forward end of

the metal part of the nozzle will extend outwardly beyond the outer face of the plate 7 as shown in the drawing. If this joint between the metal part of the nozzle and the refractory lining were located inside the steam space 6 the steam under pressure might leak into the space outside the refractory lining and find its way downwardly into the moulten metal with undesirable results. With the joint located as it is however the issuing steam begins to expand as soon as it passes beyond the plane of the outer face of plate 7 and exerts no very great pressure at the junction of lining and casing. Inwardly the refractory lining may be turned to form as shown, and outwardly it is cylindrical for the most part so that it may be readily inserted into and removed from the steel shell 1, the latter of course giving the necessary strength to the structure. The outer end of the refractory lining must extend beyond the outer end of the metal casing, because if the line of junction between the casing and the lining corresponded with the intersection of the angles of the faces 4 and 8, the extreme end of the casing would be eaten off, giving a bad edge and consequently bad results.

I claim:

1. A nozzle of the kind described for use in disintegrating molten metals and the like, comprising a metal casing and a refractory lining extending outwardly beyond the end of the casing, and a blast ring surrounding the casing and lining and beyond which both of them extend outwardly. 95
2. An apparatus for disintegrating molten metals and the like, including a nozzle having at its outer end a bore for the passage of metal and an extensive spreader-face end surface surrounding and distinct from and beyond the bore, and having also a side wall disposed at an acute angle to the line of extension of the nozzle, and the bore of the nozzle being vacant, and unobstructed at its discharge end, and a blast ring surrounding the end of the nozzle and beyond which the end of the nozzle extends outwardly, substantially as set forth. 105
3. An apparatus for disintegrating molten metal and the like, including a nozzle circular in cross section having at its outer end a bore for the passage of metal and an extensive spreader-face end surface surrounding and distinct from and beyond the bore, and having also a side wall disposed at an acute angle to the line of extension of the nozzle and the bore of the nozzle being vacant, and unobstructed at its discharge end, and a blast ring surrounding the end of the nozzle and beyond which the end of the nozzle extends outwardly, substantially as set forth. 110
4. An apparatus for disintegrating molten metal and the like, including a nozzle having

ing at its outer end a bore for the passage of metal and an extensive spreader-face end surface surrounding and distinct from and beyond the bore and having also a side wall disposed at an acute angle to the line of extension of the nozzle, and the bore of the nozzle being vacant, and unobstructed at its discharge end, and an open blast ring surrounding the end of the nozzle, providing a continuous circular outlet for the disintegrating blast.

In testimony whereof I affix my signature.

EVERETT J. HALL.
